UNITED STATES PATENT OFFICE.

EMIL KREUSER, OF MECHERNICH, GERMANY.

ELECTROMAGNETIC ORE-SEPARATOR.

SPECIFICATION forming part of Letters Patent No. 638,129, dated November 28, 1899.

Application filed May 12, 1899. Serial No. 716,606. (No model.)

To all whom it may concern:

Be it known that I, EMIL KREUSER, retired director of Royal Mines, a citizen of Germany, residing at Mechernich, Rhine Province, Germany, have invented certain new and useful Improvements in Electromagnetic Ore-Separators, of which the following is a specification.

This invention relates to electromagnetic ore-separators which consist of cylindrical bar-magnets having wire coils through which electric currents are passed and which are arranged with their poles of opposite sign revolving near to each other, the surfaces of such poles constituting the working magnetic field for separating the ore which is passed between them. When two such cylindrical bar-magnets are magnetized, they exercise a strong attraction to each other, which tends to lessen the distance between them, and consequently to do away with the air-space between them necessary for carrying on the ore-separating process. Heretofore it was sought to prevent such approach of the cylinder-magnets either by making the axial bearing sufficiently strong to resist the attraction or by the application of springs between the bearings; but these means only effect the object in an imperfect manner. According to the present invention any such approach of the cylinder-magnets is effectually prevented by providing on the ends thereof abutment or pressure rings, those of the one magnet being made to bear against those of the other magnet, so as to take the pressure due to the magnetic attraction, and thus maintain a constant distance between the operative polar fields. At the same time these abutment or pressure rings may be made to serve for transmitting the rotary motion of the one magnet to the other one. For these purposes the magnetic cylindrical pole-surfaces are provided either directly at each end or separate therefrom with rings of non-magnetic material—such, for instance, as brass, vulcanite, paper material, and the like. Iron rings might also be used if carried on a non-magnetic base. These rings being made to project in such manner that the ring of the one magnet is made to bear firmly against the ring of the second magnet,

the two are pressed together with a force corresponding to the magnetic attraction, and they thus insure a constant distance or air-space being maintained between the poles, whereby a uniform degree of attraction is exercised by these upon the material passed between them. If now the one cylindrical magnet is driven by suitable external power, the said rings or polar-distance keepers will act as frictional driving-gear, whereby the rotary motion of the one cylinder-magnet will be imparted to the other one. As these rings take the entire pressure due to the magnetic attraction, the bearings of the cylinder-magnet axes are entirely relieved of such pressure, so that these have only to support the weight of the cylinder-magnet.

It will be seen that by this invention all toothed gearing such as has been employed heretofore for transmitting the rotary motion of the one cylinder-magnet to the second one is dispensed with.

The relative speeds of rotation of the two cylinder-magnets can be varied by correspondingly varying the diameter of the pressure-rings or polar-distance keepers of the one magnet relatively to those of the other one, which variation of speed offers in many cases advantages in the separation of the ores. Lastly, such polar-distance keepers may be so arranged as to be readily changed, so that if a number of these of varying relative proportional sizes are provided the relative speeds of the two cylinder-magnets, as also the polar distance thereof, and consequently the polar field, can be changed.

In the accompanying drawings, Figure 1 is a detail longitudinal sectional view of two cylindrical electromagnets having the pressure-rings secured against the end surfaces of the magnets. Fig. 2 is a similar view showing the manner in which the pressure-rings can be changed, and Fig. 3 is a vertical sectional view of a magnetic separator embodying my invention.

A and A' are the two cylinder-magnets, which are made to revolve in contrary directions. B B' represent the wire-windings thereof, the current passing through which effects the magnetizing of the cylinders.

r are the conductor-rings fixed in an insu-

lated manner upon the axes C and C' of the cylinders.

d is the wire leading from the winding to the contact-brush rings r.

- 5 The pressure-rings D D' are secured by screws S on end pieces F, which are preferably made of non-magnetic material, such as brass, vulcanite, paper material, and the like. It will be seen that the rings D D' can be 10 readily removed and replaced by others of different diameters. Thus in Fig. 1 the pressure-ring D' of cylinder-magnet A' is of smaller diameter than the pressure-ring D of A, so that A' will revolve at a greater speed 15 than A. On passing an electric current through the cylinder-magnets these tend to approach each other as near as possible. This is prevented by the polar-distance keepers or pressure-rings, which are thus pressed firmly 20 against each other, so that on the one magnet being rotated the said rings transmit the rotation in the contrary direction to the other magnet.

It will be obvious that in place of making 25 the polar-distance keepers of annular form they may also be made as complete disks, although the annular form is preferred for the reasons above stated.

Fig. 3 shows a section of a magnetic separator provided with cylindrical magnets A A' 30 constructed according to this invention. The axes C C' revolve in bearings e g and f h, fixed to the framing L. The sliding contact-rings r are keyed to the axes on which they 35 are mounted, respectively, and are insulated therefrom, while the brushes m n o p and leads d convey the current for exciting the magnets. The lower cylinder is revolved by means of the gearing P and drives the upper 40 cylinder through the contact-rings D D'.

Having thus particularly described and ascertained the nature of this invention and

the best means I know for carrying the same into practical effect, I claim—

1. In electromagnetic ore-separators, two revoluble cylindrical electromagnets having rings at their ends the rings of the one electromagnet being made to bear against the rings of the other electromagnet so as to maintain a constant polar distance between the magnets against their mutual attraction, substantially as described. 45

2. In electromagnetic ore-separators, two revoluble cylindrical electromagnets having rings at their ends the rings of the one electromagnet being made to bear against the rings of the other electromagnet, so as to maintain a constant polar distance between the magnets and at the same time serve to transmit the rotary motion of the one magnet 55 to the other one, substantially as described. 60

3. In electromagnetic ore-separators two revoluble cylindrical electromagnets having rings at their ends the rings of the one electromagnet being made to bear against the 65 rings of the other electromagnet, said rings being of different diameters so as to impart different speeds of rotation to the two electromagnets, substantially as described.

4. In electromagnetic ore-separators two 70 revoluble cylindrical electromagnets having rings at their ends the rings of the one electromagnet being made to bear against the rings of the other electromagnet, said rings being removable so that by changing them 75 the polar distance between the magnets can be varied, substantially as described.

In testimony whereof I have hereunto set my hand in presence of two subscribing witnesses.

EMIL KREUSER.
